APPLIANCE FOR PURIFYING TOBACCO
SMOKEMaurice Farvish Lautman, Hot Springs, Ark.;
Minnie E. Lautman, executrix of Maurice F.
Lautman, deceased

Application June 6, 1938, Serial No. 211,971

2 Claims. (Cl. 131—187)

The invention relates to an improved method and appliance for purifying tobacco smoke and has for its primary object the provision of an improved method of the character indicated whereby noxious or injurious ingredients may be readily removed from tobacco.

Another object of the invention is the provision of an improved appliance of the character indicated so constructed and arranged that the purifying element may be readily removed and replaced when desired.

Other objects will appear hereinafter.

The invention consists in the improved method and appliance hereinafter described and claimed.

The invention will be best understood by reference to the accompanying drawing forming a part of this specification and in which

Fig. 1 is a side view of a smoker's appliance in the form of an ordinary cigarette holder and which is capable of use in carrying on the method;

Fig. 2 an enlarged longitudinal section of the same;

Fig. 3 a longitudinal section of a filtering tube employed in the appliance;

Fig. 4 a side view, shown partially in section, of the filtering tube and illustrating a fresh filtering element being inserted in the filtering tube and the used filtering element being ejected thereby from the tube;

Fig. 5 an enlarged section taken substantially on line 5—5 of Fig. 2;

Fig. 6 a view similar to Fig. 3 but showing a modified form of filtering element;

Fig. 7 a view similar to Fig. 4 and showing a fresh filtering element being inserted and the used filtering element being expelled thereby; and

Fig. 8 a section taken substantially on line 8—8 of Fig. 6.

The embodiment of the invention illustrated in the drawing comprises a smoker's appliance consisting of a hollow stem 10 having a bell mouth 11 at one end for the reception of a cigarette 12 or other article to be smoked therein.

A stop bead or shoulder 13 is formed in the stem 10 adjacent the inner end of the mouth 11 and a removable tube 14, preferably made of glass, is arranged to be inserted in the stem 10 and provided with a flange or shoulder 14' to engage and contact with the stop shoulder or bead 13 and thereby limit the inward movement of the tube 14 in the stem 10, as shown in Fig. 2. A filtering element 16 is preferably formed of a semi-rigid wire wound with an absorbent, fibrous material to a thickness to fairly snugly fit the interior of the tube 14 and somewhat shorter than

the same, and is inserted as shown in said tube before the tube is inserted in the stem 10. The filtering element 16 has been impregnated with ethylene glycol or other chemical having the property of extracting and retaining nicotine and coal tar derivatives from smoke passed therethrough or thereover. The filtering element 16 may also be impregnated with menthol if desired. The tube 14 is of sufficient length to protrude slightly from the end of the stem 10 as shown, and a mouthpiece 15 is threaded on said stem to engage the protruding end of said tube and hold it nicely in place, as shown in Fig. 2.

By this arrangement, a filtering element is provided which will remove the nicotine and coal tar derivatives from tobacco smoke before they pass to the mouth of the smoker, thereby removing injurious ingredients from the smoke.

By making the filtering element of semi-rigid material as described it will have sufficient longitudinal stiffness so that when it is desired to insert a fresh element in the tube 14, insertion of the fresh element will eject the used element as indicated in Fig. 4. In this way removal and replacement of the filtering element may be readily accomplished whenever desired.

In the modification illustrated in Figs. 6, 7, and 8, a straight cylindrical filtering element is shown which is also impregnated with ethylene glycol, or other chemical for the purpose of extracting nicotine and coal tar derivatives from smoke passing therethrough or thereover, and may also be impregnated with menthol as before.

While I have illustrated and described the preferred method and appliance for carrying the invention into effect, these are capable of variation and modification without departing from the spirit of the invention. I therefore do not wish to be limited to the precise details disclosed, but desire to avail myself of such variations and modifications as fall within the scope of the appended claims.

I claim:

1. The combination with a stem of a smoker's appliance having an internal stop adjacent one end thereof, of a tube removably mounted therein, seating against said stop and protruding from the other end of said stem; a mouthpiece threaded on the other end of said stem and contacting with the protruding end of said tube; and a filtering element removably mounted in said tube.

2. The combination specified in claim 1 in which the stem is provided with a bell mouth at one end to receive a cigarette or the like and the tube stop is adjacent said bell mouth.

MAURICE FARVISH LAUTMAN.
